EDUCATIONAL TOY

Ira Gold, Chicago, Ill.

Application October 5, 1945, Serial No. 620,476

1 Claim. (Cl. 35—74)

1

My invention relates to a toy for the education and entertainment of a child.

Among the objects of my invention is to provide a toy for the education and amusement of a child. My device embodies an improved construction whereby a child may spell a word, and find proof of its correct spelling. My device also makes spelling attractive and interesting. My device is simple, improved and economical in construction, lasting in wear and fascinating in operation. It will hold the attention and interest of children and is extremely useful as a means for providing knowledge and education.

My invention also contemplates such other objects, advantages and capabilities as will later more fully appear and which are inherently possessed by my invention.

While I have shown herein a preferred embodiment of my invention, yet I wish it understood that it is susceptible of modification and change without departing from the spirit of my invention.

Referring to the drawings, Fig. 1 is a face view of my device; Fig. 2 is an edge elevational view; Fig. 3 is a sectional view on line 3—3 of Fig. 1; Fig. 4 is a detailed view of my illustrations and color scheme; Fig. 5 is a face view of the discs with the cover removed; Fig. 6 is an enlarged sectional view of the disc group; Fig. 7 is a sectional view on line 7—7 of Fig. 5.

The embodiment selected to illustrate my invention comprises a base 10 on which are anchored spaced pins 11, 12 and 13. Two of the pins 11 and 12 are preferably placed at opposite portions of the base slightly below center and the third pin 13 is placed in the upper central portion of the base between the other two pins. Rotatably mounted on pins 11 and 12 are major discs 14. Also rotatably mounted on pins 11 and 12 are minor discs 15 which are smaller in dimension than major discs 14, and are vertically spaced therefrom by spacers 16.

Around the outer margins of each of the major and minor discs 14 and 15 are spaced the letters 17 of the alphabet and a blank space. Spaced inwardly from said letters in each of said discs is a ring of spaced depressions 18 at the bottoms of which are the letters of the alphabet and a blank space. The minor discs are of such size that the marginal circle of spaced letters 17 in each of the minor discs 15 is spaced from and does not overlap the circle 18 of depressed letters in major discs 14.

A third minor disc 19 is rotatably mounted on pin 13. Said disc 19 also has a marginal circle 55

17 of spaced letters and a space and inwardly thereof a ring of spaced depressions 18 containing letters and a space. Disc 19 is partially overlapped by major discs 14 but spacers 20 on base 10 permit major discs 14 to rotate above third disc 19. The bottoms and top portions of disc 19 are free from overlapping by major discs 14 and 15.

5 A cover 21 is attached by suitable means to the back of base 10 and extends over the discs 14, 15 and 19 and is slightly spaced thereabove by build up 22 attached to the face of base 10.

10 At the outer portions of the face of the cover 21 are curved openings 23 exposing a portion of spaced depressions 18 of major discs 14.

15 Spaced inwardly from openings 23 of cover 21 are curved cut out portions 24 exposing a portion of spaced depressions 18 of minor discs 15.

20 At the upper portion of the cover 21 is a curved slot 25 exposing a portion of spaced depressions 18 of the third disc 19.

25 In the central portion of the cover are five spaced windows or holes 26, 27, 28, 29 and 30. Hole 26 is positioned to expose one of the letters or the space of marginal circle 17 of minor disc 15 on the left hand side of the device. Hole 27 is positioned to expose one of the letters or the space of marginal circle 17 of major disc 14 on the left hand side of the device. Hole 28 is positioned to expose one of the letters or the space 30 of marginal circle 17 of third disc 19. Hole 29 is positioned to expose one of the letters or the space of the marginal circle 17 of major disc 14 on the right hand side of the device. Hole 30 is positioned to expose one of the letters or the space 35 of the marginal circle 17 of minor disc 15 on the right hand side of the device.

30 A plurality of spaces 31 are provided in the cover for illustrating and spelling suggested problems for the child user.

40 Another feature of my device is the definite coloring of the discs and the central openings to guide the child. For instance minor disc to the left 15 and opening 26 are colored yellow; major disc to the left 14 and opening 27 are blue; third disc 19 and opening 28 are red; major disc to the right 14 and opening 29 are green and minor disc to the right 15 and opening 30 are orange. Other colors could of course be used.

45 For illustration of use, a child sees "horse" shown in one of the spaces 31. He notes the H is yellow so he dials yellow minor disc 15 to left until H is at the lower corner of curved opening 24. This positions H in yellow window 26. The O is blue so he dials blue major disc 14 on the left until O is at the lower corner of cut out portion 23.

This positions O in blue window 21. R being red, he dials red third disc 19 until R is at the extreme right in slot 25. This positions R in red window 28. S is green, so he dials green major disc 14 on the right until S is at the lower corner of cut out portion 23. This positions S in green window 29. The final letter E is orange, so he dials orange minor disc 15 on the right until E is at the lower right hand corner of opening 24. This positions E in orange window 30.

This completes the correct spelling of "horse" for the child's information and amusement.

The child finds proof of the correct spelling of "horse" in space 31. This will confirm his correct spelling of "horse" in windows 26, 27, 28, 29 and 30.

Any word from two to five letters may be spelled by the child by use of the dials and the result will be shown in the windows. When less than five letters are used, the space in the last one, two or three dials is dialed so that the space on the marginal circle will register in the windows.

My depressions 18 are formed as follows: My discs 14, 15, and 19 have cut therethrough, a plurality of holes. The bottoms of said holes are covered by a backing of paper or other suitable thin material, on which the letters or other markings appear. The backing being thin, and behind the discs, and not filling the holes cut in the thicker discs, leaves the depressions into which the child may place his fingers for dialing.

The outer ends of curved slots 23, 24, and 25, act as stops in the dialing for determining the letter or other marking chosen to be dialed.

Having thus described my invention, I claim:

An educational toy comprising a base, a pair of spaced pins attached to opposite portions of said base, a major disc rotatably mounted on each of said pins, a minor disc rotatably mount-

ed on each of said pins, spacers spacing said major discs vertically from said minor discs, a third pin attached to said base between said pair of pins, a third disc rotatably mounted on said third pin, all of said discs having a marginal circle of spaced letters and spaced inwardly therefrom a ring of letters, said circle of said minor discs spaced from said ring of said major discs so as not to overlap same, a cover attached to said base, said cover having curved slots for exposing portions of said rings of letters of all of said discs so that said discs may be turned from the front of the toy, said cover also having a plurality of spaced windows each exposing one at a time of the letters of said circles of each of said discs, said windows being in alignment so that the letters exposed through said windows may spell out a word, said discs adapted to be moved until desired letters of said rings are positioned at the lowermost corners of said slots to produce corresponding letters of said marginal circles to be exposed through said windows.

IRA GOLD.
